UNITED STATES PATENT OFFICE.

GUSTAVUS G. WAGNER, OF NEW YORK, N. Y.

INDICATING TIME BY GAS-PRESSURE.

SPECIFICATION forming part of Letters Patent No. 234,358, dated November 9, 1880.

Application filed April 7, 1880. (No model.)

To all whom it may concern:

Be it known that I, GUSTAVUS G. WAGNER, a citizen of the United States, residing at New York, in the county and State of New York, 5 have invented new and useful Improvements in Indicating Time, of which the following is a specification.

The general object of this invention is to utilize the pressure of gas in the street gas- 10 mains of a city or town for the purpose of indicating to the inhabitants certain periods of time, as the hours or half-hours, such time being determined at the gas-works.

This invention is illustrated in the accompanying drawing, which shows the apparatus 15 generally employed.

The letter A designates a gas-main, which extends from the gas-reservoir, a portion of which is shown at B, and the major part of 20 which is laid down in the streets of a city or town, as well known.

C designates a service-pipe, whereby gas is conveyed from the gas-main to a building; and D a gas-pressure indicator, connected to the 25 gas-main through the medium of the service-pipe, such indicator being in most cases located within the building. This gas-pressure indicator may be constructed in a variety of ways well known to those skilled in the art, 30 and needs no description.

In carrying out my invention the indicator D is so arranged that it becomes set in an intelligible manner when the pressure of the gas in the gas-main rises to a degree above or beyond the maximum normal pressure—namely, 35 the pressure required to supply the city or town with gas for illuminating purposes—that is to say, the indicator is necessarily thus arranged, whereas it is optional to arrange the same to show also a lower degree of pressure.

At intervals of an hour, a half-hour, or any other period that circumstances or convenience may dictate, I increase the pressure of the gas in the gas-main A to a degree above 45 the maximum normal pressure therein by letting on an additional quantity of gas from the reservoir; and since the indicator D is set by that means the same is practically a time-piece corresponding to the one whereby the periods 50 at which the gas-pressure is increased is de-

termined. Hence if a number of pressure-indicators corresponding to this indicator D are distributed throughout a city or town the measure of time at the gas-works becomes the standard for the whole of such city or town. 55

In the gas-main A is arranged the usual gas-supply valve E. In connection with this gas-supply valve I use what I term a "time-valve," F, the same being arranged in a branch pipe, G, which is connected to the gas-main A on opposite sides of the gas-supply valve. This time-valve F may be constructed in various ways, and by its means the pressure of the gas in the gas-main A can be increased independently of the supply-valve E, making the latter 60 a regulator merely for the normal pressure of the gas, which is a desideratum; but it is obvious that the gas-supply valve E also is adapted to the purpose of the time-valve F.

With the time-valve F, I connect a mechanism which is constructed to open and close the same automatically at fixed intervals, so that the time-valve is rendered self-acting.

A mechanism adapted to the purpose of opening and closing the time-valve F can be 75 readily devised by a skilled mechanic, and a description thereof is therefore deemed unnecessary.

The general location of the mechanism referred to is shown at G, and its connection 80 with the time-valve is effected by gearing H or other suitable means.

What I claim as new, and desire to secure by Letters Patent, is—

1. The within-described method of indicating time by connecting to a street gas-main a suitable gas-pressure indicator and increasing the pressure of the gas in such gas-main to a degree above the maximum normal pressure therein at fixed intervals, thereby setting the 85 indicator.

2. The combination, with a gas-main and the gas-supply valve to such main, of a branch pipe connected to the gas-main on opposite sides of the supply-valve, a time-valve arranged in the branch pipe for the purpose of increasing the pressure of the gas independently of the supply-valve, and a gas-pressure indicator connected to the gas-main, substantially as described, for the purpose set forth. 95 100

3. The combination, with a gas-main and the gas-supply valve to such main, of a branch pipe connected to the gas-main on opposite sides of the supply-valve, a time-valve arranged in the branch pipe for the purpose of increasing the pressure of the gas independently of the supply-valve, a mechanism constructed to automatically open and close the time-valve at fixed intervals, and a gas-pressure indicator connected to the gas-main, sub-

stantially as described, for the purpose set forth.

In testimony whereof I have hereunto set my hand and seal in the presence of two subscribing witnesses.

GUSTAVUS G. WAGNER. [L. S.]
